UNITED STATES PATENT OFFICE.

ARTHUR J. KNOWLES, OF CHATTANOOGA, TENNESSEE.

DESIGN FOR THE SURFACE OF A BOTTLE.

57,438.

Specification for Design.

Patented Mar. 29, 1921.

Application filed September 3, 1920. Serial No. 408,033. Term of patent 14 years.

To all whom it may concern:

Be it known that I, ARTHUR J. KNOWLES, a citizen of the Commonwealth of Australia, residing at Chattanooga, in the county of Hamilton and State of Tennessee, have invented a new and ornamental Design for a Bottle-Surface, of which the following is a specification, reference being had to the accompanying drawing, forming a part hereof.

The figure is an elevation of a bottle showing my new design.

The design comprises upright, parallel

faces on the exterior of the bottle, the alternate of said faces being stippled or formed with slight elevations which give said alternate faces the appearance of being covered with frost or moisture condensation.

I claim:

The ornamental design for the surface of a bottle, as shown.

In testimony whereof I have signed my name, this 23rd day of August, in the year one thousand nine hundred and twenty.

ARTHUR J. KNOWLES.
